E. W. FENN

ELEVATOR DOOR

Filed Aug. 27, 1920

Patented Apr. 22, 1924.

1,491,599

UNITED STATES PATENT OFFICE.

EMORY W. FENN, OF CHICAGO, ILLINOIS, ASSIGNOR TO THE PEELE COMPANY, OF BROOKLYN, NEW YORK, A CORPORATION OF NEW YORK.

ELEVATOR DOOR.

Application filed August 27, 1920. Serial No. 406,306.

To all whom it may concern:

Be it known that I, EMORY W. FENN, a citizen of the United States, residing at Chicago, in the county of Cook and State of Illinois, have invented certain new and useful Improvements in Elevator Doors, of which the following is a specification, reference being had therein to the accompanying drawings, which form a part thereof.

10 My invention relates to elevator doors, and more particularly to elevator doors of the pass type employing two sections oppositely movable in relation to each other and having movement in a vertical plane 15 with a horizontal component, so that the doors at one opening in a shaft in opening, will pass to a horizontal plane parallel with, and overlap, closed doors at an adjacent opening.

20 Doors of the type to which my invention relates, have movement upon a single rail as to all doors in a shaft, which rail has two vertical sections occupying parallel planes, the section nearer to the wall of the elevator shaft being located adjacent the meeting point of the doors when closed, the other or longer section being spaced farther away from the wall of the shaft at the sills and lintels of the door openings and having a 25 gap therethrough into which the upper or lower guide shoes of the respective door sections may pass, and oblique sections connecting said vertical sections.

When the doors are closed, the shoes carried thereby adjacent the meeting point of the doors, engage a vertical section of the rail adjacent this point, and other shoes carried by the door are disengaged from the rail but are engaged by a switch mechanism adapted to impart the desired movement thereto to cause their engagement with, or disengagement from, the rail section more remote from the wall of the shaft with the opening or closing of the door.

35 This construction forms no part of my present invention, however, such being made the subject matter of separate applications for Letters Patent.

The door of my invention is essentially 40 of what is known as the "truckable type", employing a truck bar of sufficient width to approximately span the gap between the sill of the door opening and the elevator car when the door is open, the horizontal 45 component of movement when opening the

door necessitating the employment of a truck bar having a section offset with relation to the door and projecting towards the sill of the door opening, so as to compensate for this horizontal component of 50 movement. While in the type of door above described the rail construction will hold the doors against the wall of the elevator shaft adjacent the door opening when the door is open, it is desirable, and sometimes 55 required, that the doors when in this position be held by means independent of the rails. Furthermore, in this type of door, when it is open, no support is afforded the offset truck bar section intermediate the 60 jambs of the door opening, apart from the retaining bolts securing this section upon the frame of the door.

With these conditions in mind, I so construct the door that when it is in the closed 65 position, it will be positively locked against horizontal movement away from the wall of the shaft by means carried by said wall as distinguished from the holding means 70 carried by the wall angle bar of the rail structure. In securing this result, the locking means must be so constructed and arranged that it will not interfere with the horizontal component of movement of the doors in opening and closing same, and will 75 not bind in a manner to interfere with the free starting of the doors when opening same and the full closing of the doors. The locking means is so constructed as to 80 co-operate with the angle bar frame of the door, thus avoiding any gaps through which flame and smoke may pass from or into the shaft in the event of fire.

The locking means carried by the wall of 85 the shaft adjacent the sill of the door is also utilized as a support for the projecting section of the truck bar when the door is open, having the two-fold effect of reinforcing said door against vertical stresses of loads passing thereover, and of preventing the force 90 of the impacts of the vehicle carrying such loads being transmitted to the guides or rails with a resultant possibility of a loosening or 95 disarrangement thereof or of the wall angle bar, thus supplementing the action of the usual supporting bracket carried by said bar, and imparting to the device the added functional possibility of relieving the rail from 100 transverse or compressive stresses. By this construction, I secure points of support for 105 110

the door adjacent the sill and adjacent the edge of the wall angle bar, thus effectively preventing sagging of the door or skewing thereof under the stresses of loads passing 5 thereover.

I am also enabled to use a pass type door of any desired width without the necessity for increasing the bulk or strength of the rail structure, since while the door is in use, in 10 either the opened or the closed position, any unusual stresses thereon will be transmitted directly to the wall of the shaft, and not be sustained by the rail structure itself.

The invention consists primarily in an elevator door embodying therein a lower door section composed of an angle bar frame having the inwardly directed flanges presented toward the wall of the shaft, an upper door section, a guide rail consisting of a short 20 vertical section adjacent the meeting point of said door sections, a long vertical section parallel therewith and a connecting oblique section, said long section being positioned farther from the wall of the shaft than said 25 short section, whereby when opening and closing the door said lower section will have vertical movement while upon said vertical rail sections respectively, and a vertical movement with a horizontal component 30 while upon said oblique section, a fitting having a downwardly presented tongue mounted on the wall of the shaft adjacent the sill of the door opening, the length of said tongue being no greater than the length of 35 said short rail section below the meeting point of the door sections, and a housing carried by the panel of said door section adapted to inclose said fitting, whereby the vertical flange of the lower rail of the lower door section will pass between said tongue 40 and the wall of the shaft and lock said section in relation to the wall of the shaft, when the door is closed; and in such other novel features of construction and combination of 45 parts as are hereinafter set forth and described, and more particularly pointed out in the claims hereto appended.

Referring to the drawings,

Fig. 1 is a condensed view of an elevator 50 door embodying my invention, upon a vertical section midway between the jambs of the door opening, the door being shown in the closed position;

Fig. 2 is a similar view with the door in 55 the opened position;

Fig. 3 is a cross-sectional view of the door structure taken in part on the meeting line of the door sections and in part upon a lower horizontal section of the lower door section; 60 and

Fig. 4 is a diagrammatic view of the guide rail.

Like letters refer to like parts throughout the several views.

65 In the accompanying drawings, I have

shown an embodiment of the invention in a pass type door in which both of the sections have a horizontal component of movement during a portion of the vertical movement of the doors when opening and closing, although it is apparent that the invention may be adapted to a pass type door in which one of the sections has only a vertical movement in a single plane. 70

In the drawings, I have omitted the switch 75 mechanism operative adjacent the sill and lintel of the door for ensuring the desired parallel movement of the sections in their entirety when having a horizontal component of movement, since this mechanism 80 forms no part of the present invention.

In the embodiment of the invention shown in the drawings, the wall of the elevator shaft is shown at *a*, the lintel of a door opening therein at *a'*, the sill of said opening at *a''* and the side jambs of said opening at *a'''* and *a''''*. Secured to the wall of the shaft upon opposite sides of each door opening is the usual wall angle bar *b* which may be secured in place in any desired manner 90 as by means of ordinary foundation bolts.

Carried by each of said wall bars is a single guide rail composed of a short vertical section *c* extending adjacent the meeting point of the two door sections, a long vertical section *c'* adjacent and below the sill of the door opening, an oblique section *c''* connecting said first named sections, a long vertical section *c'''* adjacent and above the lintel of the door opening, and an oblique section *c''''* connecting said section *c'''* with the short section *c*. The sections *c'* and *c'''* have the usual gaps *d*—*d'* therein for permitting the engagement and disengagement of the top or the bottom shoe of the upper or the lower door sections respectively, with the long rail section co-operating therewith, at the limit of the horizontal component of movement of the door sections. 100

Mounted upon the guide rail or track, which may be of any desired construction, are two door sections *e* and *f* provided with the usual shoes co-operating with the guide rail or track structure, and with the switch 115 mechanism above referred to but not shown in the drawings. Each of the sections *e* and *f* is provided with a rectangular angle iron frame closed by means of a panel *e'* and *f'*, which in the form of the invention shown is of corrugated metal, although if desired an ordinary metal sheathed wooden panel may be used. The inwardly directed flanges of the angle bar frame of each door section are positioned on that side of the door adjacent the wall of the shaft so as to permit the inwardly directed flange of the top bar of the upper door section and the corresponding flange of the bottom bar 120 of the lower door section, to be utilized as a 125

- part of the locking means to relieve the rail structure from the force of any impacts upon the door when it is closed, which includes co-operating locking members secured 5 directly to the wall of the shaft adjacent the lintel a' and sill a^2 . Said door section frames are engaged with their co-operating locking members only when the door is in the closed position, it being essential to have 10 the rail section c extend for a sufficient distance upon opposite sides of the meeting line of the two door sections to ensure the engagement and disengagement of these locking members with and from the frame 15 of the door in closing and opening same prior to the operative effect of the oblique sections c^2 and c^4 of the rail in imparting a horizontal component of movement to both sections.
- 20 The locking member co-operating with the top rail of the upper door section consists of a metal fitting g having an upwardly extending tongue g' spaced away from the door a distance slightly greater than the 25 thickness of the flange of the frame of the door section e with which it co-operates. This fitting is bolted or otherwise secured to the wall of the shaft immediately above the lintel of the door and projects within the 30 shaft toward the door to an extent which necessitates the employment in the door section e of a vertical housing h extending between the top and bottom bars of the frame of said section, which incloses said 35 fitting and permits the door to come to rest in close proximity to the wall of the shaft upon the completion of the closing movement.
- Slightly below the sill a^2 is a fitting i 40 having a downwardly projecting tongue i' and an upwardly projecting stud i^2 which terminates on substantially the level of the sill a^2 , which construction is provided because the lower fitting is adapted to co-operate 45 with the lower door section in a manner to hold it against horizontal displacement when the door is open, as well as when it is closed. The door section f is provided with a housing j similar to the housing h of the section e , which incloses the fitting i while exposing the inwardly presented flange of the bottom rail of the door section so as to permit its entering the 50 space between the tongue i' and the wall of the elevator shaft.
- The number of fittings $g-i$ will vary with the width of a door, an increase in the 55 number of such fittings and housings involving a mere duplication of parts.
- 60 The housings $h-j$ are designed primarily to afford clearance to permit movement of the door sections in relation to the fittings $g-i$, but have the incidental function of bracing the door intermediate the side rails
- thereof. When metal sheathed doors are 65 used, these bars serve as mullions to which the vertical edges of the corrugated sheets may be attached, and co-operate with the frame of the door and with other such housings to confine the metal sheathed 70 wooden panels, when such are used. The depth of the housing is immaterial, so long as they afford the desired clearance for said fittings when the door is approaching and has reached the closed position.
- 75 The two door sections e and f are connected in the usual manner, the hanger bar f^2 of the door section f being adapted to engage the usual stops k carried by the wall angle bar b to support and maintain the top bar of the door on substantially the same plane as the sill of the door opening to facilitate the closing of the gap between the elevator car and said sill when the door is open, which is a characteristic incidental 80 to a door of the truckable type. With a pass type door, however, I provide a supplemental truck bar section of a width so as to pass between the door jambs a^3 and a^4 when the door is closed, which supplemental truck bar shown at m is in the form of an angle iron bolted or otherwise secured to the top bar of the lower door section. This bar m is of a width to engage and seat upon the fitting i when the door is open, and is provided with a socket opening which preferably extends entirely therethrough, adapted to receive the stud i^2 upon said fitting, and thus co-operate with the stops k in sustaining the loads upon the door as vehicles 85 pass from the floor of the building to the elevator car, and relieving the tracks and the wall angle bars from at least a portion of the vertical strains from such moving loads. In addition to this characteristic, 90 the stud i^2 co-operating with said bar m , will hold the door section f against horizontal displacement under the force of impacts of loads therewith and thus entirely 95 relieve the track structure from stresses therefrom.
- 100 The door section e has an overhung astragel n adapted to co-operate with the supplemental truck bar m when the door is in the closed position. At o I have shown 105 the usual flame angle upon the door section f .
- The detailed construction of the door sections is immaterial to the invention, which is equally applicable to corrugated metal, or metal sheathed wooden paneled doors, the 110 invention relating more particularly to those structural characteristics by which the frame of the door may be utilized to form a positive lock while the door is closed, which will serve to hold the door sections 115 close to the wall of the elevator shaft, and relieve the track structure from stresses developed by blows upon said door sections.
- 120
- 125

The operation of the herein described door structure is substantially as follows:—

When a door is closed, the relation of parts will be as shown in Fig. 1 of the drawings. In opening the door the track section *c* will limit the movement of the door sections to a directly vertical movement for a distance sufficient to permit the inwardly directed flange of the top bar of the door section *e* and of the bottom bar of the door section *f*, to pass beyond the end of the tongues *g'* and *i'* respectively. After the flanges have cleared said tongues, a horizontal component of movement is introduced in the movement of the doors by the oblique sections *c²* and *c⁴*, said door sections as they pass onto the long sections *c'* and *c³* of the guide rail or track being spaced away from the wall a distance sufficient to permit them to pass a door closing an opening above and below the door opening closed by the door being operated.

As the doors reach the fully opened position, the truck bar section *m* will seat upon the fitting *i* and thus afford a support for said supplemental truck bar intermediate the jambs of the door, the lateral extensions of the hanger bar *f²* at the same time engaging the stops *k*, thus serving to support the door section with the upper edge or truck bar portion thereof on substantially the level of the sill *a²*. In this manner the load upon the door will be sustained in part by the wall angle bars *b* and in part by the fitting *i* carried by the wall of the elevator shaft. The stud *i²* of the fitting *i*, as the door comes to rest with the bar *m* upon said fitting, will enter the opening in said bar and thus prevent displacement of the door inwardly of the shaft when a load is passing thereover, relieving the rail section *c²* and the wall angle bar from such stresses from the load.

In closing the door, the operation will be the reverse of that described, each door section being brought upon the plane which it occupies when the door is closed before the top rail of the section *e* and the bottom rail of the section *f* reaches the operative relation to the tongues *g'* and *i'* respectively.

It will be observed that the tongues *g'* and *i'* operatively engage the door only when it is approaching the closed position or is in this position, the door automatically engaging and disengaging said tongues as a result of the movements of the door as determined by the track structure.

The stops *k* and the fitting *i* will prevent the door section *f* from falling, in the event of breakage of the suspension cable connecting the two door sections, while the fitting *g* will act similarly as to the door section *e*.

The use of the fittings *g* and *i* will relieve

sides of the door opening from unusual stresses thereon, to an extent to avoid the necessity for employing heavy metal stock in such structures.

While the housings *h* and *j* are shown as being vertical channels extending the entire width of each door section, it is apparent that if desired the recessed portion forming this housing need extend only a short distance from the top bar of the frame of the section *e* and the bottom bar of the frame of the section *f* sufficient to afford clearance to permit horizontal movement of the door sufficient to clear the fittings *g* and *i*.

It is not my intention to limit the invention to the detailed construction of the track structure nor of the door sections, my present invention relating more particularly to the means for binding both sections with relation to the shaft when the door is closed, with the specific characteristic of utilizing the binder fitting adjacent the sill of the door opening as a support for the projecting truck bar section which is essential to a door of the pass type.

Having described the invention, what I claim as new and desire to have protected by Letters Patent, is:—

1. An elevator door embodying therein a lower door section composed of an angle bar frame having one of the sets of flanges parallel to and presented toward the wall of the shaft, an upper door section, a guide rail consisting of a short vertical section adjacent the meeting point of said door sections, a long vertical section parallel therewith and a connecting oblique section, said long section being positioned farther from the wall of the shaft than said short section, whereby when opening and closing the door said lower door section will have vertical movement while upon said vertical rail sections respectively, and a vertical movement with a horizontal component while upon said oblique section, a fitting having a downwardly presented tongue mounted on the wall of the shaft adjacent the sill of the door opening, the length of said tongue being no greater than the length of said short rail section below the meeting point of the door sections, and a housing carried by the panel of said door section adapted to inclose said fitting, whereby the vertical flange of the lower rail of the lower door section will pass between said tongue and the wall of the shaft and lock said section in relation to the wall of the shaft, when the door is closed.

2. An elevator door embodying therein a lower door section, an upper door section composed of an angle bar frame having one of the sets of flanges parallel to and presented toward the wall of the shaft, a guide rail consisting of a short vertical sec-

- tion adjacent the meeting point of said door sections, a long vertical section parallel therewith and a connecting oblique section, said long section being positioned farther from the wall of the shaft than said short section, whereby when opening and closing the door said upper section will have vertical movement while upon said vertical rail sections respectively, and a vertical movement with a horizontal component while upon said oblique section, a fitting having an upwardly presented tongue mounted on the wall of the shaft adjacent the lintel of the door opening, the length of said tongue being no greater than the length of said short rail section above the meeting point of the door sections, and a housing carried by the panel of said upper door section adapted to inclose said fitting, whereby the vertical flange of the upper rail of the upper door section will pass between said tongue and the wall of the shaft and lock said section in relation to the wall of the shaft, when the door is closed.
3. An elevator door embodying therein upper and lower door sections each composed of an angle bar frame having one of the sets of flanges thereof parallel to and presented toward the wall of the shaft, a guide rail consisting of a short vertical section adjacent the meeting point of said door sections, long vertical sections parallel therewith extending adjacent and beyond the lintel and the sill of the door opening respectively, and oblique sections connecting said vertical sections respectively, said long sections being positioned farther from the wall of the shaft than said short sections, whereby when opening and closing the doors, the sections thereof will have vertical movement while upon said vertical rail sections respectively, and a vertical movement with a horizontal component while upon said oblique sections respectively, a fitting having a downwardly presented tongue mounted on the wall of the shaft adjacent the sill of the door opening, a second fitting mounted on the wall of the shaft adjacent and above the lintel of the door opening, having an upwardly presented tongue, the length of said tongues respectively being no greater than the distance said door sections respectively travel upon said short rail section, and housings carried by the panels of said door sections respectively each adapted to inclose the fitting associated with that section, whereby the vertical flange of the lower rail of the lower door section, and the vertical flange of the upper rail of the upper door section, will pass between the tongue of the fitting associated with said section and the wall of the shaft, and lock said sections in relation to the wall of the shaft, when the door is closed.
4. An elevator door embodying therein a lower door section composed of an angle bar frame having one of the sets of flanges parallel to and presented toward the wall of the shaft, an upper door section, a guide rail consisting of a short vertical section adjacent the meeting point of said door sections, a long vertical section parallel therewith and a connecting oblique section, said long section being positioned farther from the wall of the shaft than said short section, whereby when opening and closing the door said lower section will have vertical movement while upon said vertical rail sections respectively, and a vertical movement with a horizontal component while upon said oblique section, a fitting having a downwardly presented tongue mounted on the wall of the shaft adjacent the sill of the door opening, the length of said tongue being no greater than the length of said short rail section below the meeting point of the door sections, and a housing consisting of a channel bar extending vertically between the upper and the lower bars of said frame and adapted to inclose said fitting, whereby the vertical flange of the lower rail of the lower door section will pass between said tongue and the wall of the shaft and lock said section in relation to the wall of the shaft, when the door is closed.
5. An elevator door embodying therein a lower door section, an upper door section composed of an angle bar frame having one of the sets of flanges parallel to and presented toward the wall of the shaft, a guide rail consisting of a short vertical section adjacent the meeting point of said door sections, a long vertical section parallel therewith and a connecting oblique section, said long section being positioned farther from the wall of the shaft than said short section, whereby when opening and closing the door said upper section will have vertical movement while upon said vertical rail sections respectively, and a vertical movement with a horizontal component while upon said oblique section, a fitting having an upwardly presented tongue mounted on the wall of the shaft adjacent the lintel of the door opening, the length of said tongue being no greater than the length of said short rail section above the meeting point of the door sections, and a housing consisting of a channel bar extending vertically between the upper and the lower bars of said frame and adapted to inclose said fitting, whereby the vertical flange of the upper rail of the upper door section will pass between said tongue and the wall of the shaft and lock said section in relation to the wall of the shaft, when the door is closed.
6. An elevator door embodying therein upper and lower door sections each composed of an angle bar frame having one of the sets of flanges parallel to and thereof presented toward the wall of the shaft, a guide rail consisting of a short vertical section adjacent the meeting point of said door sections, a long vertical section parallel therewith and a connecting oblique section, said long section being positioned farther from the wall of the shaft than said short section, whereby when opening and closing the door said lower section will have vertical movement while upon said vertical rail sections respectively, and a vertical movement with a horizontal component while upon said oblique section, a fitting having a downwardly presented tongue mounted on the wall of the shaft adjacent the sill of the door opening, the length of said tongue being no greater than the length of said short rail section below the meeting point of the door sections, and a housing consisting of a channel bar extending vertically between the upper and the lower bars of said frame and adapted to inclose said fitting, whereby the vertical flange of the lower rail of the lower door section will pass between said tongue and the wall of the shaft and lock said section in relation to the wall of the shaft, when the door is closed.

- the meeting point of said door sections, long vertical sections parallel therewith extending adjacent and beyond the lintel and the sill of the door opening respectively, and oblique sections connecting said vertical sections respectively, said long sections being positioned farther from the wall of the shaft than said short sections, whereby when opening and closing the doors, the sections thereof will have vertical movement while upon said vertical rail sections respectively, and a vertical movement with a horizontal component while upon said oblique sections respectively, a fitting having a downwardly presented tongue mounted on the wall of the shaft adjacent the sill of the door opening, a second fitting mounted on the wall of the shaft adjacent and above the lintel of the door opening, having an upwardly presented tongue, the length of said tongues respectively being no greater than the distance said door sections respectively travel upon said short rail section, and housings consisting of channel bars extending between the upper and the lower bars of said sections respectively and each adapted to inclose the fitting associated with that section, whereby the vertical flange of the lower rail of the lower door section, and the vertical flange of the upper rail of the upper door section, will pass between the tongue of the fitting associated with said section and the wall of the shaft, and lock said sections in relation to the wall of the shaft, when the door is closed.
7. An elevator door embodying therein a lower door section composed of an angle bar frame having one of the sets of flanges parallel to and presented toward the wall of the shaft, a supplemental truck bar carried by and extending substantially flush with the top of the upper bar of said door section and normally projecting between the jambs of the door opening, said truck bar being of a width to span the gap between said upper bar and the sill of the door when the door is open, and having an opening therein, an upper door section, an offset astragal carried by the lower bar of the frame of said upper door section adapted to inclose said supplemental truck bar when the door is closed, a guide rail consisting of a short vertical section adjacent the meeting point of said door sections, a long vertical section parallel therewith and a connecting oblique section, said long section being positioned farther from the wall of the shaft than said short section, whereby when opening and closing the door said lower door section will have vertical movement while upon said vertical rail sections respectively, and a vertical movement with a horizontal component while upon said oblique section, a fitting having a downwardly presented tongue mounted on the wall of the shaft adjacent the sill of the door opening, the length of said tongue being no greater than the length of said short rail section below the meeting point of the door section, and an upwardly projecting stud adapted to enter the opening in said supplemental truck bar, and a housing carried by the panel of said door section adapted to inclose said fitting, whereby the vertical flange of the lower rail of the lower door section will pass between said tongue and the wall of the shaft and lock said section in relation to the wall of the shaft, when the door is closed.
8. An elevator door embodying therein a lower door section composed of an angle bar frame having one of the sets of flanges parallel to and presented toward the wall of the shaft, a supplemental truck bar carried by and extending substantially flush with the top of the upper bar of said door section and normally projecting between the jambs of the door opening, said truck bar being of a width to span the gap between said upper bar and the sill of the door when the door is open, and having an opening therein, an upper door section, an offset astragal carried by the lower bar of the frame of said upper door section adapted to inclose said supplemental truck bar when the door is closed, a guide rail consisting of a short vertical section adjacent the meeting point of said door sections, a long vertical section parallel therewith and a connecting oblique section, said long section being positioned farther from the wall of the shaft than said short section, whereby when opening and closing the door said lower door section will have vertical movement while upon said vertical rail sections respectively, and a vertical movement with a horizontal component while upon said oblique section, a fitting having a downwardly presented tongue mounted on the wall of the shaft adjacent the sill of the door opening, the length of said tongue being no greater than the length of said short rail section below the meeting point of the door section, and an upwardly projecting stud adapted to enter the opening in said supplemental truck bar, and a housing carried by the panel of said door section adapted to inclose said fitting, whereby the vertical flange of the lower rail of the lower door section will pass between said tongue and the wall of the shaft and lock said section in relation to the wall of the shaft, when the door is closed.
9. An elevator door embodying therein a lower door section, a guide rail adapted to impart a horizontal component of movement to said lower door section during a portion of its opening or closing movement, whereby said section will be spaced away from the wall of the shaft when the door is open and will be closely adjacent said shaft when the door is closed, a supplemental truck bar carried by said door section adapted when the door is open to span the gap between same and the sill of the door opening, and means carried by the wall of the shaft adjacent the sill of the door opening adapted to

engage said truck bar when the door is open, and transmit vertical and horizontal stresses thereon to the wall of the shaft.

10. An elevator door embodying therein
 5 a lower door section composed of an angle bar frame having one of the sets of flanges parallel to and presented toward the wall of the shaft, an upper door section, a guide rail consisting of a short vertical section adja-
 10 cent the meeting point of said door sections, a long vertical section parallel therewith and a connecting oblique section, said long section being positioned farther from the wall of the shaft than said short section,
 15 whereby when opening and closing the door said lower section will have vertical movement while upon said vertical rail sections respectively, and a vertical movement with a horizontal component while upon said
 20 oblique section, and co-operating means carried by the wall of a shaft adjacent the sill of the door opening and by said lower door section, whereby said co-operating means will operatively engage each other upon the
 25 completion of the closing movement of the door and lock said section in relation to the wall of the shaft.

11. An elevator door embodying therein
 a lower door section composed of an angle
 30 bar frame having one of the sets of flanges parallel to and presented toward the wall of the shaft, an upper door section, a guide rail consisting of a short vertical section ad-

jaent the meeting point of said door sections, long vertical sections parallel therewith and connecting oblique sections, said long sections being positioned farther from the wall of the shaft than said short section, whereby when opening and closing the door said door sections will have vertical move- 35
 40 ment while upon said vertical rail sections respectively, and a vertical movement with a horizontal component while upon said oblique section, co-operating means carried by the wall of a shaft adjacent the sill of the door opening and by said lower door section, whereby said co-operating means will operatively engage each other upon the completion of the closing movement of the door and lock said section in relation to the 45
 50 wall of the shaft, and co-operating means carried by the wall of a shaft adjacent the lintel of the door opening, and said upper door section, whereby said co-operating means will operatively engage each other 55 upon the completion of the closing movement of the door and lock said upper section in relation to the wall of the shaft.

In witness whereof I have hereunto affixed
 my signature, in the presence of two sub- 60
 scribing witnesses, this 29 day of July, 1920.

EMORY W. FENN.
